UNITED STATES PATENT OFFICE.

FRED HANSEN, OF PULCIFER, WISCONSIN.

WRENCH.

SPECIFICATION forming part of Letters Patent No. 534,064, dated February 12, 1895.

Application filed March 8, 1894. Serial No. 502,940. (No model.)

To all whom it may concern:

Be it known that I, FRED HANSEN, a citizen of the United States, residing at Pulcifer, county of Shawano, and State of Wisconsin, have invented a new and useful Improvement in Wrenches, of which the following is a specification.

The object of the invention is to provide a wrench which will be capable of operating in obscure and out of the way places, and one which can be variously adjusted to suit the size of the nut or the position in which it is arranged. This end I attain by certain novel features of construction and combination and arrangement of parts that will be more fully described hereinafter and finally embodied in the claims.

In the accompanying drawings: Figure 1 represents a perspective view of my wrench; Fig. 2, a longitudinal section thereof; Fig. 3, a detail perspective of the head; Fig. 4, a detail perspective of the pawl bar for holding the head; Fig. 5, a detail section.

The reference letter *a* indicates the shank or body of the wrench, which is preferably cylindrical in shape and provided at its rear end with a squared stud *a'*, upon which the operating rod *b* is arranged and held in place by means of a nut *b'*. By this device, rod *b*, 30 the wrench is operated.

Formed longitudinally in the shank *a* is the passage *c*, which communicates with the front end of the shank and is provided for the reception of the longitudinally-movable rod *c'*. The rod *c'* has its front end reduced, at *d*, and has the cross-rod *d'* fixed to its middle and projecting beyond its sides and into the longitudinally-elongated slot *e* of the shank. The purpose of this construction is 40 to allow the rod *c'* a limited longitudinal movement in the passage *c*.

The rear end of the rod *c'* is reduced, at *e'*, and screw-threaded so as to receive the nut *e'*, which serves as a shoulder for the 45 spring *f* which is located in the passage *c* and which operates to push the rod *c'* forward. One end of the cross-rod *d'* extends beyond the body *a* and is formed with an enlargement or head thereon by which it may be 50 grasped, so as to move the rod *c'* in its passage *c*.

The front end of the body or shank *a* is

formed with two integral lugs *g* thereon, which are duplicates of each other and arranged oppositely. Located between these 55 lugs, and pivoted therein by the pin *f'*, is the semi-circular stud *g'* of the head *h*. The head *h* is formed with the stud *g'* thereon, and the curved rear side of the stud is formed with the notches *g''* therein, with which the 60 front end of the rod *c'* is adapted to engage. By this construction the head *h* may be locked rigidly on the shank in any position to suit the location of the nut. Formed in the head is the forwardly-projecting stud or arm *h'*, 65 which leaves an indentation *h''* in which the swinging arm or jaw *i* is pivoted by means of the pin *i'*. The arms *h'* and *i* comprise the jaws of the wrench, and the latter jaw is adapted to move toward and from the first 70 in the operation of adjusting it to the nut. This operation is effected by the female screw *k*, which is arranged in the opening *k'* of the jaw or arm *h'* and provided with a head *l* by which the screw may be revolved, while the 75 lower end of the screw is provided with a flange *l'* which prevents the screw from being removed.

Operating in the screw *k* is the threaded rod *m*, which is pivoted in the recess *m'* of 80 the jaw *i*, by means of the pin *m''*. Thus it will be seen that by operating the screw *k* the rod *m* will be drawn toward or moved away from the jaw *h'*, thereby causing jaw *i* to move similarly.

In the operation of my invention the jaw *i* is adjusted to suit the size of the nut and the head *h* adjusted on the shank to permit the operation. It will now be possible to use the wrench as ordinarily and as will be understood.

Having described my invention, I claim—

1. A nut wrench comprising in its construction a head, an arm or jaw rigid thereon, a second arm or jaw hinged to the head, a 95 threaded rod pivoted to the hinged jaw, and a female screw revolubly mounted in the fixed jaw and having the threaded rod operating therein, substantially as described.

2. In a wrench, the shank *a* having the passage *c* and slot *e*, the longitudinally-movable rod *c'* received within the passage, the cross-rod *d'* fixed to the rod and working in the slot, the rear or inner end of the rod being

threaded, the nut *e'* working on the threaded end of the rod, and the spring *f* bearing at one end against the closed inner end of the passage *c* and at the other end against the 5 nut, in combination with the wrench head *h* pivoted at the front end of the shank and having at its inner end the curved notched stud

adapted to be engaged by the front end of the rod *c'*, substantially as described.

FRED HANSEN.
